UNITED STATES PATENT OFFICE.

JEREMIAH E. MATHEWSON, OF BROAD HEATH, NEAR MANCHESTER, ENGLAND, ASSIGNOR, BY MESNE ASSIGNMENTS, TO BENJAMIN C. TILGHMAN, JR., AND RICHARD TILGHMAN, TRADING AS THE FIRM OF B. C. & R. A. TILGHMAN, OF PHILADELPHIA, PENNSYLVANIA.

APPARATUS FOR CLEANING AIR FROM SAND-BLAST APPARATUS.

SPECIFICATION forming part of Letters Patent No. 707,134, dated August 19, 1902.

Application filed September 20, 1901. Serial No. 75,743. (No model.)

To all whom it may concern:

Be it known that I, JEREMIAH E. MATHEWSON, a subject of the King of Great Britain and Ireland, residing in Broad Heath, near 5 Manchester, in the county of Lancaster, England, have made certain new and useful Improvements in Apparatus for Cleaning Air from Sand-Blast Apparatus, of which the following is a true and exact description, reference being had to the accompanying drawings, which form a part hereof.

My invention relates to apparatus for cleaning the air drawn from sand-blast apparatus, and has for its object to provide an efficient 15 device for this purpose.

The nature of my improvements will be best understood as described in connection with the drawings, in which they are illustrated, and in which—

20 Figure 1 is a side elevation of my apparatus, and Fig. 2 a front elevation of the same apparatus.

A diagrammatically indicates a sand-blast chamber, which may be of any character. B 25 is the dust-pipe leading from the said chamber and communicating directly with a fan-casing C, which in turn communicates with a delivery-pipe D, leading into the top of a water-tank, (indicated at F.) This tank is 30 shown as provided with a cleaning-door G at bottom, through which mud can be removed, and with an air-outlet pipe, (indicated at M.) It is also provided with a water-outlet pipe H, the end *h* of which enters the tank at what

35 is intended to be its water-level, (indicated at *f*.) The water-pipe H is shown provided with a valve I, by which it can be closed or regulated, and leads into a pump, (indicated at J,) said pump having a delivery-pipe K, which

40 passes, as shown, through the pipe B and is provided at its upper end with a spray-nozzle L, directed to deliver water against the blades of the fan E, contained in the casing C. As shown and as conveniently constructed, the pipe K passes through the wall of the pipe B; but it is immaterial in what manner or just where the nozzle L is introduced, so

long as it throws the water against the blades of the fan.

In operation the fan E being set in motion 50 the air is drawn from the sand-blast chamber A through the pipe B into the fan-casing C, passing through the fan-casing, through the pipe D, and down against the water in the tank F. At the same time the pump J sucks 55 the water from the tank F, drawing it through the pipe H and forcing it through the pipe K to the nozzle L, which projects it into contact with the fan-blades, insuring a most thorough admixture of water-spray with the 60 dust-laden air passing through the fan, the result of which is that the air is thoroughly cleaned by the water and all mud precipitated through the pipe B into the water in the tank F, clean air being allowed to escape 65 through the pipe M. The water-level in the tank F is maintained constant by the action of pump J, which draws off the water as fast as it rises above the determined level *f*.

Having now described my invention, what 70 I claim as new, and desire to secure by Letters Patent, is—

1. The combination with a sand-blast plant and an exhaust-conduit pipe leading from said plant and adapted to draw dust-laden air from said locality, of an exhaust-fan coupled to said conduit and a nozzle arranged to throw a jet or jets of water upon the rotating blades of the fan, whereby said water is finely divided and thoroughly mixed with the 75 dust-laden air.

2. The combination with a sand-blast plant and an exhaust-conduit pipe leading from said plant and adapted to draw dust-laden air from said locality, of an exhaust-fan coupled to said conduit, a nozzle arranged to throw a jet or jets of water upon the rotating blades of the fan, whereby said water is finely divided and thoroughly mixed with the dust-laden air, and a receptacle connected with 85 the delivery side of the fan to receive the mud mixed with the air and permit the cleaned air to escape.

3. The combination with a sand-blast plant

and an exhaust-conduit pipe leading from | said plant and adapted to draw dust-laden air from said locality, of an exhaust-fan coupled to said conduit, a nozzle arranged to | 5 throw a jet or jets of water upon the rotating blades of the fan whereby said water is finely divided and thoroughly mixed with the dust-laden air, a water-tank having means for

maintaining water at approximately the same level, and a delivery-pipe leading from the 10 fan to a point in the tank above the water-level.

J. E. MATHEWSON.
